P.L.C.(57) **CLAIM**

We claim the ornamental design for a nozzle, as shown and described.

DESCRIPTION

FIG. 1 is a right, front, and top perspective view of a nozzle; FIG. 2 is a front elevational view thereof, where a rear elevational view thereof is a mirror image of FIG. 2; FIG. 3 is a left side elevational view thereof; FIG. 4 is a right side elevational view thereof; FIG. 5 is a top plan view thereof, where a bottom plan view thereof is a mirror image of FIG. 5; FIG. 6 is a sectional view thereof taken along line 6-6 in FIG. 2; FIG. 7 is a sectional view thereof taken along line 7-7 in FIG. 3; and, FIG. 8 is a sectional view thereof taken along line 8-8 in FIG. 3.

The broken lines show portions of a nozzle which form no part of the claimed design.

The “dash-dot” broken lines are for the purpose of showing the bounds of the claimed design, and form no part thereof.
